Patented February 9, 1904.

UNITED STATES PATENT OFFICE.

ANDREW C. BOSSELMAN, OF NEW YORK, N. Y.

DESIGN FOR A CUP.

SPECIFICATION forming part of Design No. 36,780, dated February 9, 1904.

Application filed December 31, 1902. Serial No. 137,375. Term of patent 7 years.

To all whom it may concern:

Be it known that I, ANDREW C. BOSSELMAN, a citizen of the United States, and a resident of the city of New York, borough of Manhattan, 5 in the county and State of New York, have invented a new, original, and ornamental Design for a Cup, as shown in the accompanying drawings, in which—

Figure 1 is a perspective view of a cup, 10 showing my design; and Figs. 2, 3, and 4 are

side elevations of the same from different points of view.

I claim as new and desire to secure by Letters Patent—

The ornamental design for a cup as herein 15 shown.

ANDREW C. BOSSELMAN:
